UNITED STATES PATENT OFFICE.

EDWIN W. VAN FLEET, OF LOS ANGELES, CALIFORNIA, ASSIGNOR OF ONE-HALF TO
DONATO COZZOLINO, OF LOS ANGELES, CALIFORNIA.

MOVING-PICTURE THEATER.

1,348,069.

Specification of Letters Patent. Patented July 27, 1920.

Application filed April 7, 1917. Serial No. 160,418.

To all whom it may concern:

Be it known that I, EDWIN W. VAN FLEET, a citizen of the United States, and a resident of Los Angeles, in the county of 5 Los Angeles and State of California, have invented a new and Improved Moving-Picture Theater, of which the following is a full, clear, and exact description.

My invention relates to moving-picture theaters. An object of the invention is to 10 eliminate the seats in proximity to the screen, which are undesirable on account of distortion and disorder induced in the optic nerve of the patrons occupying such seats.

Another object of the invention is to provide a moving-picture theater in which the 15 seating capacity is not diminished although seats in proximity to the screen are eliminated.

With the above and other objects in view, the nature of which will more fully appear 20 as the description proceeds, the invention consists in the novel construction, combination and arrangement of parts as herein 25 fully described, illustrated and claimed.

In the accompanying drawings, forming part of the application, similar characters of reference indicate corresponding parts in both views.

Figure 1 is a longitudinal section through 30 a moving-picture theater embodying my invention; and

Fig. 2 is a horizontal section on line 2—2, Fig. 1.

Referring to the drawings, 3 and 3' are 35 facing screens each adapted to receive images projected thereupon from a projecting machine 4 located on a platform 5 provided in the central part of the theater between the screens. The floor space between the screens is provided with rows of chairs 6 and 6', the rows of chairs 6 facing the screen 3, and the rows of chairs 6' facing the rows 40 3'. But it will be noted that the rows of chairs 6', although facing the screen 3', are closer to the screen 3 and, therefore, remote from the screen 3'. The same is true in 45 regard to the rows of chairs 6. By this provision there are no chairs facing a screen in 50 proximity to the screen.

The rows of chairs 6 and 6' are separated

by a partition 7 extending transversely between the screens 3 and 3'. The height of this partition 7 is such that the view of the screen 3 or 3' from the row of seats nearest 55 to the partition is not obstructed by said partition. The platform 5 is also of such a height and width that the view of the screen is not obstructed from the last row.

If desired, seats may be provided on the 60 platform 5. The seats on the platform 5 will be arranged in a manner such that those nearest to the screen will face the screen, that is, in a manner different from the arrangement on the floor space, for on the 65 upper floor space the row of seats nearest to the screen face the opposite screen. From the above description it will be seen that in my arrangement seats in close proximity to the receiving screen are eliminated, but 70 the capacity of the theater is not reduced.

The space between the rows of seats 6 and 6' where the partition 7 is provided can also serve for the orchestra. In which case, the 75 central part of the partition 7 may be removed and a platform or seats for the orchestra provided.

The entrances and exits 8 are preferably provided on each side of the partition in the side walls of the theater. End exits 9 80 can also be provided on each side of the screen.

I claim:

1. In a moving picture theater, facing receiving screens, a series of rows of chairs 85 facing each of the screens, a partition separating the series of rows facing the opposite screens, the series of rows facing the screens being located on the side of the partition remote from the screen the rows are 90 facing, and a platform above the partitions adapted to receive the means for projecting images on the screens.

2. In a moving picture theater, facing receiving screens, means for projecting images on each of said screens, a partition between the screens, and a plurality of rows of chairs on each side of said partition, the rows of chairs between the partition and the screen facing the other screen. 95

EDWIN W. VAN FLEET.
